US0D1016807S

(12) **United States Design Patent** (10) Patent No.: **US D1,016,807 S**
(45) Date of Patent: ** Mar. 5, 2024

(54) **WATCH**

(71) Applicant: **Daoyuan Zheng**, Shenzhen (CN)

(72) Inventor: **Daoyuan Zheng**, Shenzhen (CN)

(**) Term: **15 Years**

(21) Appl. No.: **29/824,281**

(22) Filed: **Jan. 24, 2022**

(51) LOC (14) Cl. **14-02**

(52) U.S. Cl.

USPC **D14/344**; D10/38

(58) **Field of Classification Search**

USPC D10/30-39, 128, 132; D11/3; D14/344,

D14/345, 440, 444-446

CPC G04B 37/005; G04B 37/0058; G04B

37/084; G04B 37/087; A45C 11/10;

A45C 11/12; A45C 2011/001
